UNITED STATES PATENT OFFICE.

GEORGE MANIERRE, OF MILWAUKEE, WISCONSIN, ASSIGNOR TO TICKNOR-MANIERRE COMPANY, OF MILWAUKEE, WISCONSIN, A CORPORATION.

LOADING MACHINE.

1,037,784.

Specification of Letters Patent. Patented Sept. 3, 1912.

Application filed October 6, 1911. Serial No. 653,161.

To all whom it may concern:

Be it known that I, GEORGE MANIERRE, a citizen of the United States, residing at Milwaukee, county of Milwaukee, and State 5 of Wisconsin, have invented certain new and useful Improvements in Loading Machines, of which the following is a specification.

This invention relates to improvements in 10 loading apparatus and more particularly to the portable type and the primary object of the invention is to provide an improved apparatus of this character for conveniently, quickly and economically loading the material into cars.

A further object is to provide an improved apparatus of this character adapted for universal movement and for movement into and out of the car and having means 20 for connecting a delivery chute to the distributing hopper of the loader whereby the universal movement of the loader will not be interfered with.

To the attainment of these ends and the 25 accomplishment of other new and useful objects, as will appear, the invention consists in the features of novelty in the construction, combination and arrangement of the several parts hereinafter more fully described and claimed and shown in the accompanying drawings illustrating an embodiment of the invention and in which—

Figure 1 is a view partly in elevation and partly in section showing an improved apparatus of this character, constructed in accordance with the principles of this invention in use for loading a box car. Fig. 2 is a detail side elevation of the loading apparatus. Fig. 3 is an enlarged detail sectional 40 view on line 3—3, Fig. 1. Fig. 4 is a sectional view on line 4—4, Fig. 6. Fig. 5 is a detail top plan view of a portion of the supporting structure of the loading apparatus. Fig. 6 is a sectional view on line 45 6—6, Fig. 4. Fig. 7 is an enlarged detail sectional view on line 7—7, Fig. 2.

Referring more particularly to the drawings and in the present exemplification of the invention, the numeral 10 designates 50 generally the railroad tracks upon which the car 11 is adapted to run, and arranged alongside of the tracks 10 are tracks 12, upon which the car 13 supporting the loading apparatus to be hereinafter described,

is adapted to travel, and this car 13 may be 55 propelled in any desired or suitable manner, and in the present exemplification of the invention the ordinary and well known trolley 14 is provided for this purpose.

Mounted upon the car or truck 13 are 60 spaced members 15 extending transversely thereacross and these members are preferably of an I-beam structure between which are journaled members 16, which latter are pivoted to the members 15 for rocking 65 movement. In the present exemplification of this invention two of these members 16 are provided and each is provided with spaced arms 17 projecting therefrom, one of the arms on each of the members 16 being 70 preferably arranged in proximity to each of the members 15. The members 16 are spaced longitudinally from each other, as shown, and the respective arms 17 of these members 16 are pivotally connected 75 by their free extremities to I-beams 18, which latter are of a length somewhat greater than the length of the members 15, and are adapted to be moved toward and away from the members 15 when the members 16 are 80 rocked. The loading apparatus to be presently described is supported by these members 18 and inasmuch as the members 18 are adapted to be raised and lowered with respect to the truck or car 13, it will be apparent 85 that the loading apparatus supported thereby may be correspondingly raised and lowered in accordance with the height of the floor of the car 11.

Any suitable means may be provided for 90 rocking the members 16 to raise and lower the members 18 and a suitable and efficient means for accomplishing this result comprises a bar or rod 19, which is pivotally connected to depending arms or projections 95 20 on the members 16, and which arms or projections are preferably arranged midway of the arms 17 of the respective members 16. A cross bar or member 21 is provided which is secured to the lower faces of 100 the members 15 to extend across the space therebetween and depending from this member 21 is a bracket 22 comprising spaced members between which is pivotally supported a tubular member 23. The member 105 23 is so arranged that one extremity of the bar or rod 19 will pass therethrough to project beyond the end thereof and this ex-

tremity 24 of the bar or rod is provided with threads, as shown, for the reception of a nut or collar 25, which latter is threaded thereon. This nut or collar 25 is adapted to abut the tubular member 23 for the purpose of holding the members 18 in their adjusted positions, as the tubular member will receive the strain or pull of the bar or rod 19 due to the weight of the superposed structure. It will thus be seen that when the nut or collar 25 is adjusted on the threaded extremity 24 of the bar or rod 19, the members 18 will be raised or lowered according to the direction of adjustment of the nut or collar.

15 Supported by the members 18 is a carriage designated generally by the reference numeral 26, which latter may be of any desired construction, the body portion of which is adapted to project into the space 20 between the members 18. The carriage is provided with bearings 27 which project over the outside of the respective members 18 and rollers 28 are journaled in these bearings so as to project into the space between 25 the flanges of the outer faces of the members 18. The rollers 28 are of a diameter to substantially fill the spaces and are spaced from each other longitudinally of the members 18 a sufficient distance so that the carriage 26 will be always maintained in a proper position with relation to the members 18, and will be held against displacement by the weight of the loading apparatus, with respect to the members 18. Projecting forwardly from the carriage 26 is 30 an arm or extension 29, which is preferably arranged centrally of the carriage, as shown more clearly in Fig. 5, and this arm may be of any desired length preferably of a 35 length to project through the door 30 in the side of the car 11 when the truck 13 is in the proper position with respect to the car. An arm 31 is pivotally connected by one extremity to the free extremity of the 40 arm or extension 29 and a pivot pin 32 is provided for this purpose and about which the arm 31 is adapted to swing.

A yoke-shaped member 33 is arranged at the outer extremity of the arm 31 and 45 is pivotally connected therewith to move about an upright pivot and a conveyer frame designated generally by the reference numeral 34 as shown in Fig. 2 is supported by the yoke-shaped member 33 for movement about a horizontal pivot 35, the conveyer frame being connected with the yoke-shaped member between its extremity, and an endless conveyer 36 is provided which travels upon the conveyer frame 34 upon 50 which the material to be loaded is deposited from a distributing hopper 37. This hopper 37 is mounted upon a carriage 38 adapted to travel upon the conveyer frame 34, preferably the upper members 39 of the 55 frame and is held against displacement with

respect to the conveyer frame by means of clips 40, which latter are connected with the carriage 38 and extend under an edge of the respective upper members 39 of the conveyer frame. Racks 41 are supported by the conveyer frame which is adapted to be engaged by a gear 42 on the carriage 38 and a crank handle 43 is provided by means of which the gear 42 may be rotated. Guards 41^a are provided for the racks 41 and may be loosely attached to the carriage 38. It will thus be apparent that by the rotation of the gear 42 by the handle 43, the carriage 38 and the hopper 37 supported thereby may be moved longitudinally with respect to the conveyer frame 34. A locking dog or pawl 44 is provided, which cooperates with the gear 42 and serves as a means for locking the gear 42 against retrograde movement, thereby holding the carriage 38 and its hopper 37 in the adjusted position. A portion of the conveyer frame projects rearwardly as at 45 beyond the point of pivotal support 35 for the reception of a motor 46, the shaft of which latter is connected by means of the usual connections with the pulley 47 over which the endless conveyer 36 passes and which pulley 47 acts as a drive pulley for imparting motion to the conveyer. Handles 48 are also provided by means of which an operator may readily shift the conveyer frame 34 and the arm 31 so as to position the loading apparatus with respect to the car. In order to elevate or lower the free end of the conveyer, any suitable means may be provided and a suitable and efficient mechanism for accomplishing this result will now be described.

A tubular member 49 is pivotally connected as at 50 with the yoke-shaped member 33 and a bar or rod 51 passes loosely through a collar 52, which latter is pivotally supported from the extension 45 of the conveyer frame. The adjacent extremities of the tubular member 49 and the bar or rod 51 are connected preferably by being threaded one into the other as shown, such as by providing the end of the member 49 with interior screw threads and the adjacent extremity of the bar or rod 51 with threads. The tubular member 49 also serves as a receptacle for a lubricant. The portion of the threaded extremity of the bar or rod 51 is protected by a sleeve 53 supported by the tubular member 49 and is of a diameter somewhat larger than the diameter of the bar or rod 51 and a removable cap 53^a closes the open end of the sleeve 53 and is provided with the opening through which the bar or rod loosely passes. A crank 54 is provided on the other extremity of the bar or rod 51 by means of which the rod 51 may be rotated in the sleeve 52. When thus rotated it will be screwed into or out of the sleeve 53.

53 and inasmuch as the bar or rod is connected with the conveyer frame 34 it will be apparent that as the bar or rod 49 is fixed, the conveyer frame 34 will be moved 5 about the horizontal pivot 35 in one direction or the other to raise or lower the free extremity of the conveyer frame, according to the direction of rotation of the crank 54.

The apparatus thus described is supported 10 for bodily movement upon the truck 13 so as to be moved into and out of the car at will and the carriage 26 which supports this mechanism and which moves upon the truck 13 is adapted to be advanced or retracted, 15 preferably by means of a motor 55 (see Figs. 1 and 5) which is mounted upon the carriage 26. The shaft of the motor projects beyond both sides thereof and secured to the extremities of the shaft are gears 56, 20 which latter coöperate and have engagement with the racks 57 on the members 18, as shown more clearly in Figs. 1 and 3. It will thus be apparent that when the motor is operated and the shaft thereof rotated, 25 the gears or pinions 56 will be rotated and as they mesh with the racks 57 the carriage 26 will be advanced or retracted according to the direction of rotation of the motor shaft and which direction of rotation 30 may be controlled by the operator at will in the ordinary and well known manner.

Arranged alongside of the track 10 and preferably the side opposite to the side on which the tracks 12 are located, is a support 35 58, which latter supports a fixed chute 59 provided with a section 60 at the free end thereof. This section 60 is supported for rotary motion with respect to the chute 59 in any suitable manner, preferably by means 40 of a connecting member 61 having flanged portions 62 carried by the inner end of the section 60, which latter is held in position by means of pivot pins 62^a passing through the members 61 and brackets 63, which latter are secured to the adjacent end of the chute 59. With this construction it will be apparent that the section 60 will not only be supported by the chute 59 against displacement with respect thereto but is adapted 45 to be rotated with respect to the chute 59 about the pivot points 62^a. Another chute section 64 is supported by the chute section 60 and is adapted to be adjusted longitudinally with respect thereto so that 50 the section 64 may be projected into the car 11 through said opening 65 in the side thereof, and so that the free extremity of this section 64 may be disposed to discharge into the delivery hopper 37 of the loader in a 55 manner to be set forth. This section 64 is connected with the section 60 in any desired or suitable manner, preferably by means of brackets 66 supported by the chute section 60 and with which the section 64 has sliding 60 engagement. It will thus be seen that the

section 64 may be adjusted longitudinally with the section 60 upon the brackets 66 while at the same time the section 64 may be rotated with the section 60. In order to support the free end of the section 64 when 70 it is being withdrawn or inserted into the car through the opening 65, a suitable counterbalancing means may be provided such as a weight 67 which may be connected with a flexible member 68 passing over a pulley 69 75 and the free end of this flexible member 68 is connected as at 70 adjacent the free end of this chute section 64.

The chute section 64 is connected with the hopper 37 when the loading apparatus is in use by means of a clamp 71 which latter is provided with a flange 72 (see Figs. 4 and 6) adapted to engage under a flange 73 on the edge of the hopper 37. The clamp 71 may be of any desired length and is of a 80 configuration to conform to the contour of the flanged edge of the hopper 37. This clamp 71 is provided with rearwardly projecting ears or extensions 74 spaced from each other and a rock shaft 75 is journaled 85 by its extremities in the ears or projections 74. Hook-shaped members 76 are secured by one extremity to the rock shaft 75 (see particularly Figs. 4 and 6) adjacent the ears or extensions 74 and are of a length and 90 configuration to extend over and engage the inner edge of the flanged portion 73 of the hopper. In order to hold the hook-shaped member 76 in operating position so as to secure the clamp 71 against accidental displacement with respect to the hopper, suitable elastic members 77 may be provided, which members tend normally to move the hook-shaped members into operating positions or into the positions shown in Figs. 4 95 and 6, to secure the clamp against displacement. A handle 78 is also provided which is connected with the rock shaft 75 and this handle serves the purpose of adjusting the hook-shaped members 76 by a pressure on 100 the handle, to move the hook-shaped members against the tension of the elastic members 77 and out of engagement with the edge of the hopper 37 to permit the clamp 71 to be disengaged from the hopper. This clamp 105 is connected or secured to the section 64 of the chute by means of a member 79, which latter is provided with projecting portions 80 between which the tubular portion 81 of an arm 82 projects. This tubular portion 81 is connected with the member 79 by means of a fastening pin or rod 83 passing through the projections 80 and the tubular member and serves as means whereby the arm 82 is 110 pivotally connected with the member 79. The free extremity of the arm 82 is also provided with a tubular portion 84 at the outer extremity thereof which is arranged 115 transversely with respect to the member 81. This tubular portion 84 projects between 120 125 130

ears or extensions 85 on the clamp 71 and a fastening rod or bolt 86 passes through the extensions 85 and the tubular member 84 and serves as a means for connecting the 5 free end of the arm 82 with the clamp 71 for movement on an axis transverse to the axis about which the tubular portion 81 of the arm 82 is rotatable. It will thus be apparent that the free end of the section 64 of 10 the chute is connected to the hopper 37 for universal movement, so that when the loading apparatus is projected into the car as shown in Fig. 1, from one side of the car, the chute may be secured to the hopper 37 through the medium of the section 64 and the fastening devices just described. When thus secured the material to be loaded will 15 be delivered into the delivery hopper 37 of the loading apparatus and from the hopper 37 will be deposited upon the endless conveyor 36. When it is desired to adjust the conveyer or loader so as to elevate or lower the free end thereof or to adjust its position within the car, this may be accomplished 20 through the medium of the handles 48, and inasmuch as the chute section 64 is connected with the hopper 37 for universal movement, it will be apparent that the free movement or adjustment of the conveyer frame 34 will 25 not be interfered with. After the car has been loaded, the chute may be disconnected from the hopper by depressing the handle 78 to shift the hook-shaped member 76 and thereby permit the clamp 71 to be delivered 30 from the hopper. The loading apparatus may then be withdrawn from the car by means of the motor 55 in the manner already described. By the provision of the clamp 71, the delivery end of the chute will be connected 35 with the distributing hopper of the car loader in such a manner that the clamp will be free to slide around the edge of the hopper without becoming accidentally detached therefrom.

40 45 What is claimed as new is—

1. The combination of a delivery chute, a track adjacent said chute, a car loader also adjacent the track and separate from the chute, and means adaptably connecting the 50 delivery end of the chute with the distributing hopper of the car loader.

2. The combination of a delivery chute, a track adjacent said chute, a car loader also adjacent the track and on the side thereof 55 opposite to that on which the chute is located, and means adaptably connecting the delivery end of the chute with the distributing hopper of the car loader.

3. The combination of a delivery chute, a track adjacent the chute, a car loader also adjacent the track and separate from the chute, said car loader being supported for universal movement, and means securing the delivery end of the chute to the car loader.

60 65 4. The combination of a delivery chute,

a track adjacent the chute, a car loader also adjacent the track and separate from the chute, and a universal connection between the delivery end of the chute and the car loader.

70 5. The combination of a delivery chute, a track adjacent the chute, a car loader also adjacent the track and separate from the chute, said loader being supported for universal movement, and a universal connection for securing the delivery end of the chute to the car loader.

75 80 6. The combination of a support, a chute supported thereby and having a universally movable delivery end, a track adjacent the support, a universally movable car loader also adjacent the track, and means securing the said delivery end of the chute to the distributing hopper of the car loader to discharge thereinto.

85 90 9. The combination of a support, a discharge chute supported thereby, a track adjacent the support, a portable car loader movable adjacent the track, and adjustable with respect to the car and the delivery chute, and means for securing the delivery end of the chute to the distributing hopper of the car loader to discharge thereinto and for adjustment with the latter.

95 100 10. The combination of a support, a discharge chute supported thereby, a track adjacent the support, a portable car loader movable adjacent the track, means for projecting the loader into and out of loading position with respect to the car, and means for securing the delivery end of the chute to the loader to discharge into the distributing hopper of the loader.

105 110 11. The combination of a support, a discharge chute supported thereby, a track adjacent the support, a portable car loader movable adjacent the track, means for projecting the loader into and out of loading position with respect to the car, and means for securing the delivery end of the chute to the loader to discharge into the distributing hopper of the loader, the last said means embodying a universal connection.

115 120 12. The combination of a support, a discharge chute supported thereby, a track adjacent the support, a portable car loader movable adjacent the track, means for projecting the loader into and out of loading position with respect to the car, and means for securing the delivery end of the chute to the distributing hopper of the car loader, the last said means embodying a universal coupling supported by one of the parts and having detachable engagement with the other part.

125 130 13. The combination of a delivery chute, a track adjacent the chute, a portable car loader adjacent the track, means for projecting the loader into and out of loading position with respect to a car on the track, a

universal connection between the discharge end of the chute and distributing hopper of the loader for detachably securing the chute to the hopper, and means for supporting the said discharge end of the chute when detached from the hopper.

12. The combination of a delivery chute, a track adjacent the chute, a portable car loader adjacent the track, means for projecting the loader into and out of loading position with respect to a car on the track, a universal connection between the discharge end of the chute and distributing hopper of the loader for detachably securing the chute to the hopper, and counterbalancing means for supporting the said discharge end of the chute when detached from the hopper.

13. The combination of a delivery chute, a track adjacent the chute, a portable car loader adjacent the track and supported for universal movement, means for projecting the loader into and out of loading position with respect to a car on the track, a universal connection between the delivery end of the chute and the car loader for detachably securing the chute to the hopper, and counterbalancing means for supporting said discharge end of the chute when detached from the hopper.

14. The combination of a track, a portable car loader adjacent the track and adapted to be projected through the side door of a car on the track, a delivery chute adapted to discharge through another door of the car and into the distributing hopper of the loader, and a universal connection between the chute and the distributing hopper.

15. The combination of a track, a portable car loader adjacent the track and supported for universal movement, said car loader embodying a distributing hopper and adapted to be projected through the side door of a car on the track, a delivery chute, discharging into the distributing hopper, and a universal connection between the delivery hopper and the chute.

16. The combination of a track, a portable car loader adjacent the track and supported for universal movement, said loader embodying a distributing hopper and adapted to be projected through the side door of a car on the track, and a delivery chute discharging through a door on the side of the car opposite to the side on which the loader is located and into the distributing hopper of the loader.

17. The combination of a track, a portable car loader adjacent the track and supported for universal movement, said loader embodying a distributing hopper and adapted to be projected through the side door of a car on the track, a delivery chute discharging through a door on the side of the car opposite to the side on which the loader is located and into the distributing hopper of

the loader, and means for securing the delivery end of the chute to the said delivery hopper.

18. The combination of a track, a portable car loader adjacent the track and supported for universal movement, said loader embodying a distributing hopper and adapted to be projected through the side door of a car on the track, a delivery chute discharging through a door on the side of the car opposite to the side on which the loader is located and into the distributing hopper of the loader, and a universal connection for securing the delivery end of the chute to the said distributing hopper.

19. The combination of a track, a portable car loader adjacent the track and supported for universal movement, said loader embodying a distributing hopper and adapted to be projected through the side door of a car on the track, a delivery chute discharging through a door on the side of the car opposite to the side on which the loader is located and into the distributing hopper of the loader, and means for securing the delivery end of the chute to the distributing hopper, the said means embodying a universal coupling supported by one of the parts and having detachable engagement with the other of the parts.

20. The combination of a track, a portable car loader adjacent the track and supported for universal movement, said loader embodying a distributing hopper and adapted to be projected through the side door of a car on the track, a delivery chute discharging through a door on the side of the car opposite to the side on which the loader is located and into the distributing hopper of the loader, and means for securing the delivery end of the chute to the distributing hopper, said means being supported by one of the parts and embodying elements connected for universal movement, one of said elements detachably engaging the other of the connected parts.

21. The combination of a track, a portable car loader adjacent the track and supported for universal movement, said loader embodying a distributing hopper and adapted to be projected through the side door of a car on the track, a delivery chute discharging through a door on the side of the car opposite to the side on which the loader is located and into the distributing hopper of the loader, and means for securing the delivery end of the chute to the distributing hopper, said means being supported by one of the parts and embodying elements connected for universal movement, one of said elements being detachably connected with the other of the connected parts and for sliding movement with respect thereto.

22. The combination of a track, a portable car loader adjacent the track and supported

for universal movement, said loader embodying a distributing hopper and adapted to be projected through the side door of a car on the track, a delivery chute discharging through a door or the side of the car opposite to the side on which the loader is located and into the distributing hopper of the loader, means for securing the delivery end of the chute to the distributing hopper, 5 said means embodying a clamp supported by one of the parts for universal movement with respect thereto, and having detachable and slideable engagement with the other of said parts, and means for effecting a clamping and unclamping action of the said clamp. 10

23. The combination of a track, a portable car loader adjacent the track and supported for universal movement, said loader embodying a distributing hopper and adapted to be projected through the side door of a car on the track, a delivery chute discharging through a door on the side of the car opposite to the side on which the loader is 20 located and into the distributing hopper of the loader, means for securing the delivery end of the chute to the distributing hopper, said means embodying a clamp supported by one of the parts for universal movement 25 with respect thereto, said clamp embodying clamping hooks engaging over the edge of the other of the parts for sliding movement with respect thereto, and means tending normally to move the clamping hooks into 30 clamping positions.

24. The combination of a track, a portable car loader adjacent the track and supported for universal movement, said loader embodying a distributing hopper and adapted 40 to be projected through the side door of a car on the track, a delivery chute discharging through a door on the side of the car opposite to the side on which the loader is located and into the distributing hopper of the 45 loader, means for securing the delivery end of the chute to the distributing hopper, said means embodying a clamp supported by one of the parts for universal movement with respect thereto, said clamp embodying 50 clamping hooks engaging over the edge of the other of the parts for sliding movement with respect thereto, means tending normally to move the clamping hooks into clamping positions, and an operating handle 55 for shifting the clamping hooks against the tension of the last recited means.

25. The combination of a delivery chute, a portable car loader embodying a distributing hopper into which the chute discharges, and 60 means for connecting the chute to the said delivery hopper, said means embodying a clamp connected with one of the parts for movement on axes arranged transversely with respect to each other, and means for 65 detachably securing the clamp to the other

of the parts and for sliding movement with respect thereto.

26. The combination of a delivery chute, a track adjacent the chute, a portable car loader adjacent the track and adapted to be 70 bodily projected into and out of loading position with respect to the car, means for bodily adjusting the car loader vertically with respect to its support, and means for detachably connecting the delivery chute to 75 the distributing hopper of the loader.

27. The combination of a delivery chute, a stationary support therefor, said chute having a universal adaptable end section, a portable car loader, means for bodily projecting the loader into and out of loading 80 position with respect to a car adjacent the chute, and means for connecting said adaptable end section of the chute with the distributing hopper of the car loader. 85

28. The combination of a delivery chute, a stationary support therefor, said chute embodying sections adjustably connected together, a portable car loader, means for bodily projecting the loader into and out 90 of loading position with respect to a car adjacent the chute, means for connecting the outermost section of the chute with the distributing hopper of the car loader, and counterbalancing means for supporting the 95 free end of the outermost section when said section is detached from the said distributing hopper.

29. The combination of a delivery chute, embodying a stationary section, a section 100 rotatably connected therewith and a section connected with the second recited section for adjustment substantially longitudinally with respect thereto, a car loader into the delivery hopper of which the chute discharges, and means for suspending the delivery end of the chute. 105

30. The combination of a delivery chute, embodying a stationary section, a section rotatably connected therewith and a section 110 connected with the second recited section for adjustment substantially longitudinally with respect thereto, a car loader into the delivery hopper of which the chute discharges, a coupling adapted for universal 115 movement for securing the free end of the delivery chute to the distributing hopper of the loader, and means for supporting the said free end of the chute when detached from the hopper. 120

31. A portable car loader embodying a main support, a supplemental support mounted thereon for vertical adjustment with respect thereto, a carriage movable on the supplemental support, a car loader carried by the carriage, means for moving the carriage on its support to project the car loader into and out of loading position, and means for adjusting the said supplemental support vertically. 125

32. A portable car loader embodying a main support, a supplemental support mounted thereon for vertical adjustment with respect thereto, a carriage movable on the supplemental support, a car loader carried by the carriage, means for moving the carriage on its support to project the car loader, through the side door of a car, means for adjusting the said supplemental support vertically and a delivery chute discharging into the distributing hopper of the loader from the side of the car opposite to that on which the door through which the loader is projected.

33. A portable car loader embodying a main support, a supplemental support mounted thereon for vertical adjustment with respect thereto, a carriage movable on the supplemental support, a car loader carried by the carriage, a motor carried by the carriage for moving the carriage on its support to project the car loader into and out of loading position, and means for adjusting the said supplemental support vertically.

34. A portable car loader embodying a main support, a supplemental support mounted thereon for vertical adjustment with respect thereto, a carriage mounted to travel on the supplemental support, a car loader mounted on the carriage for universal movement with respect thereto, means for adjusting the supplemental support vertically for bodily raising or lowering the car loader, and a motor carried by the said carriage for advancing and retracting the carriage on its support.

35. A portable car loader embodying a main support, a supplemental support mounted thereon for vertical adjustment with respect thereto, a carriage mounted to travel on the supplemental support, a car loader mounted on the carriage for universal movement with respect thereto, means for adjusting the supplemental support vertically for bodily raising or lowering the car loader and embodying arms having pivotal connections with the said main and supplemental supports, and a motor carried by the said carriage for advancing and reTRACTING the carriage on its support.

36. A portable car loader embodying a main support, a supplemental support mounted thereon for vertical adjustment

with respect thereto, a carriage mounted to travel on the supplemental support, a loader support on the carriage embodying arms pivotally connected at one extremity for movement on a vertical axis, a car loader supported by the outermost arm for movement on a vertical and a horizontal axis with respect thereto, means carried by the carriage for advancing and retracting the carriage on the supplemental support, and means for adjusting the supplemental support with respect to the main support to bodily raise and lower the car loader.

37. In combination, a portable car loader embodying a main support, a supplemental support mounted thereon for vertical adjustment with respect thereto, a carriage mounted to travel on the supplemental support, a car loader mounted on the carriage for universal movement with respect thereto, means for adjusting the supplemental support vertically for bodily raising or lowering the car loader, a motor carried by the said carriage for advancing and retracting the carriage on its support, and a delivery chute separate from and discharging into the distributing hopper of the car loader.

38. In combination, a portable car loader embodying a main support, a supplemental support mounted thereon for vertical adjustment with respect thereto, a carriage mounted to travel on the supplemental support, a car loader mounted on the carriage for universal movement with respect thereto, means for adjusting the supplemental support vertically for bodily raising or lowering the car loader, a motor carried by the said carriage for advancing and retracting the carriage on its support, a delivery chute separate from and discharging into the distributing hopper of the car loader, and a universal coupling for securing the discharge end of the chute to the said distributing hopper.

In testimony whereof I have signed my name to this specification, in the presence of two subscribing witnesses, on this 11th day of February A. D. 1911.

GEORGE MANIERRE.
